United States Patent Office

Des. 227,113
Patented June 5, 1973

227,113

CHECK READER

Frank Burroughs, Kensington, Md., and Robert Springer,
Woodbridge, Va., assignors to Optical Recognition
Systems, Incorporated, Reston, Va.

Filed Apr. 19, 1971, Ser. No. 135,538

Term of patent 14 years

Int. Cl. D14—02

U.S. Cl. D26—5 C

FIG1

FIG4

FIG3

FIG2

FIG. 1 is a perspective view of the check reader embodying our new design showing the front and left side thereof;

FIG. 2 is a top plan view of the check reader shown in FIG. 1;

FIG. 3 is a left side view of the check reader shown in FIG. 1; and

FIG. 4 is a right side view of the check reader shown in FIG. 1.

We claim:

The ornamental design for a check reader, substantially as shown.
